Inventor:

Calvin T. Smith

Calvin T. Smith

UNITED STATES PATENT OFFICE.

CALVIN T. SMITH, OF ALBION, MICHIGAN.

BAG-HOLDER.

SPECIFICATION forming part of Letters Patent No. 275,086, dated April 3, 1883.

Application filed August 31, 1882. (No model.)

To all whom it may concern:

Be it known that I, CALVIN T. SMITH, of Albion, in the county of Calhoun and State of Michigan, have invented new and useful Improvements in Bag-Holders; and I hereby declare that the following is a full, clear, and exact description thereof, reference being had to the accompanying drawings, which form a part of this specification.

10 The nature of this invention relates to certain new and novel improvements in the construction of bag-holders designed to be removably attached to and adjusted upon trucks.

15 The invention consists in the peculiar construction of the hopper and means employed for securing it upon the truck, and in the means employed for securing the mouth of the bag to the hopper, all as more fully hereinafter set forth.

20 Figure 1 is a perspective view of my improved hopper and hand-truck. Fig. 2 is a rear elevation, showing the dogs for locking the hopper to place.

25 In the accompanying drawings, A represents a truck of any desired construction, except that it is provided with notches b.

B represents a hopper, which is provided with the guide-plates a, which latter embrace the side bars or handles, C, of the truck. Piv-30 otally secured to the rear face of the hopper B are the gravitational dogs D, the toes of which automatically engage with one of the series of

notches b in the handles C, and which retain the hopper in its adjusted position. Around the lower end of the hopper are secured the 35 outwardly-projecting studs or hooks e, and the central stud, d, upon the front face thereof.

E is a bolt arranged to slide within the case F, and is provided with the downwardly-projecting spurs or pins e, which are designed to 40 straddle the pin or stud d and lock the bag thereto.

In practice, the hopper being first adjusted to its proper position upon the truck, the mouth of the bag to be filled is slipped over 45 the lower end of the hopper, its edges engaging with the studs or hooks e and the stud d, and the bolt E is pushed down, causing the pins e to pierce through the bag and securely fasten it to place. 50

What I claim as my invention is—

1. In a bag-holder, and in combination with a hopper, D, having guide F, hooks e, and stud d, the bolt E, having spurs e, as specified.

2. In a bag-holder, and in combination with a hand-truck having in its handles a series of notches, b, the hopper B, having hooked guides a and gravitational dogs D, as set forth. 55

In testimony that I claim the above I hereunto set my hand.

CALVIN T. SMITH.

In presence of—

H. S. SPRAGUE,
LILLIE A. MERCUR.
